(57) **CLAIM**

We claim the ornamental design for a blower attachment for a walk-behind mower, as shown and described.

DESCRIPTION

FIG. 1 is a top perspective view of a blower attachment for a walk-behind mower of the present invention shown in use condition;

FIG. 2 is an enlarged top perspective view of a blower attachment for a walk-behind mower of the present invention;

FIG. 3 is a first side view thereof;

FIG. 4 is a second side view thereof;

FIG. 5 is a top view thereof;

FIG. 6 is a bottom view thereof;

FIG. 7 is a front view thereof; and,

FIG. 8 is a rear view thereof.

The ornamental design which is claimed is shown in solid lines in the drawings. Any broken lines in the drawings are for illustrative purposes only and form no part of the claimed design.
